UNITED STATES PATENT OFFICE

HOWARD W. STEIGER, OF LAKWOOD, OHIO

VISE

Application filed June 24, 1930. Serial No. 463,399.

This invention relates to a vise and has for its principal object to provide such an implement which shall be capable of ready and rapid adjustment to different uses and positions and which will be comparatively simple in construction while embodying various features making for durability, cheapness and strength. A further and more limited object is to provide a vise having a fixed base member and a movable base member with which one jaw is integral and which is provided with an opening through which an elongated shank portion of a sliding jaw may extend and embodying an improved guide and stop mechanism, an improved means for anchoring the movable portion at any position of rotation, an improved lubricating mechanism, and superior clamping features. Other objects will become apparent from the following description when taken in connection with the drawings.

Fig. 1 is a central vertical section taken through my improved device; Fig. 2 is a section on line 2—2 of Fig. 1; Fig. 3 is a fragmentary section corresponding to a portion of the line 3—3 of Fig. 1; Fig. 4 is a section on line 4—4 of Fig. 1; Fig. 5 is a fragmentary plan view of a portion of the sliding jaw member; and Fig. 6 is a fragmentary bottom plan view of the upper portion of the jaw member 18^a showing the mutilated threads.

In the drawings I have shown one embodiment of my invention. The upper portions of the vise are mounted on a fixed base member 10 secured to any suitable support 11 as by bolts 12. This base member includes a flange 13 for attachment to the surface 11 and a body portion provided with a central opening 14 and an annular upwardly converging open top groove 15 concentric with the opening 14. The groove 15 is provided with an opening 16 through the bottom thereof for the reception of the pyramidal head 17^a of a bolt 17. Rotatably mounted on the fixed base 10 is a jaw portion 18 which includes the jaw 18^a and a base portion 18^b which may be either integral with the jaw portion 18^a as shown, or fixedly attached thereto in any suitable manner. The base portion 18^b is provided with a downwardly

extending boss 19 which is centrally drilled and tapped to receive a stud 20 which by means of the washer 21 firmly secures the same to the fixed base 10. A socket 22 is provided in the base 18^b to receive a portion of 55 an angular guide and stop means 23. The member 23 extends through an opening in the base 18^b and the socket 22 communicates with said opening and receives the horizontally extending portion 23^a of the guide and stop 60 means 23. A supporting extension 24 is provided integral with the portion 18^b to serve as auxiliary supporting means for the elongated shank portion of the sliding jaw. Extending through the jaw member 18 is a large 65 elongated opening the upper portion of which is provided with a mutilated thread 25. An opening 26 is provided for the introduction of lubricant and may be of any approved type, such as that shown at 27, being a valved 70 nipple of the type generally used for lubricating automobiles.

Extending through the opening in the jaw member 18 is the elongated shank portion 31 of a sliding jaw 30. The sliding jaw 30 is provided with an upwardly opening lubrication chamber 32 and a downwardly opening groove or hollow interior 33. The chamber 32 is defined by vertical walls 34, and a clamping shaft 35 is journaled longitudinally of the shank portion 31 and extends through the end walls 34 of the chamber 32 and has a mutilated screw 32^a non-rotatably secured thereon in the chamber 32. The shaft 35 extends through the chamber 33 and at one end is jointed to a cylindrical member 36 which is secured thereto by means of a pin 37 extending outside the member 36 and being positionable underneath an annular overhang-flange 38 which is provided with an 80 integral stop portion 39.

The bolt 17 cooperates at its upper end with a nut 17^b which is provided with an operating handle 17^c extending therethrough. It will be obvious that the movable portion of 95 the vise may be rotated about the axis of the stud 20 when the handle 17^c is rotated to relax the clamping cooperation between the fixed base 10 and the jaw portion 18 through the action of the bolt 17^a. The angle member 23 100

will serve to limit the movement of the sliding body by contacting with the end walls of the groove 33, while serving an auxiliary guiding function by co-acting with the edges 31^a of the elongated shank portion 31, as best seen in Fig. 2. The mutilated screw 32^a is secured to the clamping shaft 35 by means of a screw 32^b and pins 32, if desired.

From the foregoing it will be evident that I provide a device which is well adapted for its intended purpose, and while I have shown and described a preferred embodiment, I wish it understood that my invention is susceptible of other embodiments and that I am limited only in accordance with the appended claims.

Having thus described my invention, what I claim is:

1. In a vise, a fixed base member, a movable base member rotatably connected to said fixed base member, a jaw member fixed to said movable base member, an opening between said base and jaw, a sliding jaw member having an elongated shank extending into said opening and provided with a groove in the bottom surface thereof, and a combined guide and stop member extending through said movable base member within the limits of said fixed base member and into said groove, and adapted to rest on said fixed base member.

2. In a vise, a fixed base member, a movable base member rotatably connected to said fixed base member, a jaw member fixed to said movable base member, an opening between said base and jaw, a sliding jaw member having an elongated shank extending into said opening and provided with a groove in the bottom surface thereof, and a combined guide and stop member extending through said movable base member within the limits of said fixed base member and into said groove, and adapted to rest on said fixed base member, said guide member comprising an angle member and said jaw having a socket receiving a portion of said guide member.

3. In a vise, a fixed base member, a movable base member rotatably connected to said fixed base member, a jaw member fixed to said movable base member, an opening between said base and jaw, a sliding jaw member having an elongated shank extending into said opening and provided with a groove in the bottom surface thereof, and a combined guide and stop member extending through said movable base member within the limits of said fixed base member and into said groove, and adapted to rest on said fixed base member, said guide member comprising an angle member and said movable base having a socket receiving a portion of said guide member.

4. In a vise, a fixed base member, a movable base member rotatably connected to said fixed base member, a jaw member fixed to said mov-

able base member, an opening between said base and jaw, a sliding jaw member having an elongated shank extending into said opening and provided with a groove in the bottom surface thereof, and a combined guide and stop member extending through said movable base member within the limits of said fixed base member and into said groove, and adapted to rest on said fixed base member, said guide member comprising an angle member and said movable base having a socket receiving a portion of said guide member, and there being an extension on said movable base member adjacent said guide and stop member adapted to serve as a support for said sliding jaw member.

5. In a vise, as a sub-combination, a sliding jaw member including a jaw portion and an elongated shank portion, said shank portion having near the end thereof remote from said jaw portion an upwardly opening chamber, a clamping shaft passing longitudinally through said shank portion extending through said chamber, and a mutilated screw non-rotatably secured on said shaft in said chamber.

6. In a vise, as a sub-combination, a sliding jaw member including a jaw portion and an elongated shank portion, said shank portion having near the end thereof remote from said jaw portion an upwardly opening chamber, a clamping shaft passing longitudinally through said shank portion extending through said chamber, and a mutilated screw non-rotatably secured on said shaft in said chamber, the bottom and side walls of said chamber being imperforate except for the openings through which said shaft extends whereby to serve as a lubricant containing chamber.

7. In a vise, as a sub-combination, a sliding jaw member including a jaw portion and an elongated shank portion, said shank portion having near the end thereof remote from said jaw portion an upwardly opening chamber, a clamping shaft passing longitudinally through said shank portion extending through said chamber, and a mutilated screw non-rotatably secured on said shaft in said chamber, said shank having a groove in the bottom thereof extending between said jaw portion and said chamber, the end walls of said groove serving as stops to limit the excursion of said sliding jaw member.

8. In a vise, as a sub-combination, a sliding jaw member, a clamping shaft journaled in said jaw member, a pin extending through said shaft and therebeyond, an annular, overhang-flange concentric with said shaft, the end of said pin extending under said overhang-flange, and a stop integral with said flange and in the path of said pin.

In testimony whereof, I hereunto affix my signature.

HOWARD W. STEIGER. 130
